GARMENT TRIMMING APPARATUS

Jacob Schlesinger, Brooklyn, N. Y., assignor to
 Man-Sew Pinking Attachment Corp., New York,
 N. Y., a corporation of New York

Application November 29, 1940, Serial No. 367,727

21 Claims. (Cl. 164—71)

My invention relates to cutting apparatus used for trimming the bottom of garments supported on a form, this operation being known as "sloping."

One of the objects of my invention is to provide novel apparatus of this nature which is power driven and which may be utilized without adaptation on any garment, irrespective of the size thereof.

Another object of my invention is to simplify the mechanism by applying a true cutting, rather than a shearing action, to the garment bottom, using a single cutting edge to accomplish this.

Another object of my invention is to combine with such sloping apparatus, means for marking the bottom of the cut garments to indicate the desired hem thereof.

Other objects of my invention will be apparent from the following description, it being understood that the above general statements of the objects of my invention are intended to describe and not to limit it in any manner.

In the accompanying drawings, showing a preferred embodiment of my invention,

Fig. 1 is an elevation showing the device in dot and dash lines ready for use, the full lines indicating the inoperative position.

Fig. 2 is a section on the line 2—2 of Fig. 1.

Fig. 3 is a section along the line 3—3 of Fig. 1.

Fig. 4 is a top plan view of the apparatus.

Fig. 5 is a section along the line 5—5 of Fig. 7.

Fig. 6 is a fragmentary section along the line 6—6 of Fig. 5.

Fig. 7 is a section along the line 7—7 of Fig. 4.

Fig. 8 is an enlarged view illustrating the cutting action.

Fig. 9 is a section along the line 9—9 of Fig. 4.

Fig. 10 is a section along the line 10—10 of Fig. 4.

Fig. 11 is a section along the line 11—11 of Fig. 5.

Fig. 12 is a section along the line 12—12 of Fig. 7.

Referring in detail to Figs. 1—3 of the drawings, the numeral 15 indicates a base supporting an electric motor 16 which through suitable reduction gearing 17, drives the pinion gear 18. The gear 18 meshes with the spur gear 19 which is secured to the shaft 20, so that said shaft 20 rotates within the ball-bearings 21 and 22. The shaft 20 is maintained against longitudinal displacement by the collar 20a. The shaft 20 supports and rotates the dress form 23 by virtue of a frictional fit with the telescoping arm 24. This frictional fit is such as to permit relative rotary

movement of the dress form when a particular force is applied thereto, as when the operator wishes to adjust the form prior to the trimming operation. However, the frictional fit is sufficient to drive the arm 24 by the shaft 20.

A rod 25, disposed rearwardly of the form 23 is provided with indicia 26 and an adjustable arm 27 with respect to which the form is raised or lowered according to the desired length of the garment to be cut. The form may be retained in its adjusted position by a manually operable mechanism well known in the art and comprising a pedal 28 adapted to actuate a rod 29 which is freely disposed in a longitudinal bore of the shaft 20 and arm 24. Suitable gripping mechanism not shown is operated by the rod 29 and serves to clutch the upper end, not shown, of the arm 24 and retain the form at the desired height. The depression of the pedal 28 serves to contract the gripping mechanism, which is normally in the expanded condition, so that the form 23 may be raised or lowered. If the pedal 28 is depressed without manually supporting the form 23, the weight thereof may overcome the frictional fit between the shaft 20 and arm 24 and the buffer spring 30 will absorb the shock of the fall thereof.

Preferably, however, the arm 24 carries a set screw 24a or equivalent device for releasably locking the same to the shaft 20 and to insure a driving connection between said arm and shaft notwithstanding frictional wear of the contacting surfaces.

Also supported on the base 15 is the post 31 to which is pivotally connected the sleeve 32 of the bracket 33. The bracket 33 is provided with ears 34 which pivotally support the cutting mechanism.

The cutting mechanism comprises the motor 35 having its shaft 36 connected to the sleeve 37 through the coupling mechanism 38 and spindle 38a which is integral with sleeve 37 and rotates within the bushing 38b. Connected to the head 39 of the sleeve 37 by the bolt 40 is a circular knife blade 41 which is thus directly driven at high speed by the motor 35.

The circular blade 41 is disposed between rotatable members 42 and 43 which assist in drawing the dress fabric through the cutting zone. These members are rotated at much less speed than the circular blade 41 which depends on great speed to perform its function properly. The members 42 and 43 are driven from the opposite end of the shaft of the motor 35 through reduction gearing 44 and spiral gearing 45 to drive the counter shaft

46. Secured to the countershaft 46 is the spur gear 47 which meshes with the gear 48, causing the sleeve 49 to rotate within the bushings 49a and 49b in the same direction as the circular blade 41 but more slowly. The member 43, being integral with the sleeve 49, is thus driven at relatively low speed. Fixed also to the lower end of the sleeve 49 is the spur gear 50, for a purpose to be hereinafter described.

The countershaft 46 is also provided with a spur gear 51 which meshes with the gear 52. The gear 52 is keyed to the member 42 and drives the spindle 53 which is journaled at one end in the bracket 54 and rotates within the bushing 37a of the sleeve 37. The bracket 54 is secured to the bosses 55 by the bolts 56, 56a and 56b, the bosses 55 being integral with the main casting generally designated as 57.

The fabric F of the dress to be cut is introduced, as will be hereinafter described, between the members 42 and 43 constituting one side of the feeding mechanism, and the member 58 constituting the other side thereof, as seen in Fig. 8.

The spur gear 50 which is fixed to the sleeve 49 meshes with the gear 59, which, secured to the spindle 60, drives the feed member 58 at the same speed as the feed members 42 and 43, although in the opposite direction. The member 58 has an annular radial groove 61 formed in the periphery thereof, said groove 61 accommodating the circular blade 41 as seen in Fig. 8.

Means are provided to separate the unit 62 and the unit 63 of the main casting 57 to permit of the initial insertion of the fabric F prior to the operation of the feeding and cutting mechanism. Such means comprise the pedal 64 operatively secured to the rod 65 which is slidably mounted in the sleeve 66 and which is disposed within the bores of ears 67 and 68 of the bracket 69 and ears 34 of the bracket 33. A pin 65a integral with the rod 65, operates within a slot formed in the sleeve 66 to prevent rotation of the rod 65.

A bell-crank lever 70, pivoted at 71 to the main casting 57 has one end thereof disposed within the recess 72 of the rod 65 while the other end thereof operatively abuts the push-rod 73 slidably supported by the bearing blocks 74 and 75. The other end of the push-rod 73, operatively abuts against the flattened end of the pin 76, which pin is fixedly received within, and secured by the bolt 77 to, the unit 62.

Depression, therefore, of the pedal 64 operates the bell-crank lever 70 which, through the push-rod 73, transmits pressure to the pin 76 and the unit 62, comprising the base section 78, the spindle 60 rotating within the sleeve 79 formed on said base section 78, the spur gear 59, the feed member 58 and the drum 80, are urged laterally by said pressure to separate the said units 62 and 63 as hereinabove noted and for the purpose described.

The slideable unit 62 is supported on the horizontal bed plate section 81 which is integral with the main frame 57 and the unit 62 is maintained against any movement other than that of the sliding above described by the tracks 82 and 83 in the form of dove-tail ribs integral with section 81. Grooves 82a and 83a, formed in the base section 78 of unit 62, slidably receive the tracks 82 and 83.

Secured to the bed plate section 81 are the pins 84 and 85 whose shanks are disposed in the elongated slots 86 and 87 formed in base 78 of the unit 62. Coil springs 88 and 89 each have one of their terminals connected respectively to

the pins 84 and 85, and the other of their terminals to the respective ears 90 and 91 of the slideable unit 62. It will thus be noted that the normal position of the unit 62, as governed by the springs 88 and 89, is that of the closed or operative position and that the abutment of member 58 against members 42 and 43, and the engagement of gears 50 and 59, will determine the limit of inward movement of unit 62. These springs permit of a slight radial yielding movement of the feed member 58 relative to the members 42 and 43 without disengagement of gears 50 and 59, so that the feed means will automatically accommodate itself to fabric materials of varying thickness and avoid excessive frictional resistance to passage of the material between said members with possible disintegration of the fabric. It will also be observed that the depression of the pedal 64 causes the unit 62 to slide the length of the elongated slots 86 and 87 against the action of the coil springs 88 and 89.

Means are also provided to automatically draw the garment downwardly and laterally to insure the accurate trimming thereof. Such means comprise the spiral gears 92 on the countershaft 46 which drive the brush 93. This brush guides the material to the cutting disk, preventing the hem from wavering. By disposing it diagonally toward the cutting disk, any accumulation of material between the brush and the cutting disk is prevented.

Referring, for example, to Figs. 4 and 10, after the fabric is introduced into the arcuate opening between the units 62 and 63 and the pedal 64 is released, the rotating brush 93 contacts the fabric and insures the unrinkled state of the garment before it is fed to the circular blade 41.

A garment must be sloped not only to its desired length, but provision must be made for a hem, the width of the hem varying as desired on different garments. Means are provided in the instant invention to indicate the desired hem-line, such means comprising the arm 94, slidably mounted on the rod 95 and adjustably secured thereto by the set-screw 96. On the arm 94 is supported the sleeve 97, housing the shell 98 (Fig. 12) which contains the marking material, such as the wax crayon 99. A coil spring 100 normally urges the wax crayon 99 outwardly and a screw-threaded cap 101 operates as an abutment for the spring 99 and closes the entrance to the sleeve 97.

The drum 80, mounted on spindle 60 and secured, for example, by the nut 102 to the grooved feed member 58, rotates therewith and normally contacts the fabric F. Spaced ribs 103 are formed on the drum 80 and when the device is in operation (Fig. 9), the fabric, fed between the drum 80 and wax crayon 99 is spacedly and intermittently marked when the ribs 103 strike the wax crayon 99, the shell 98 recoiling and emerging after each contact. In this way, the wax line is rendered more easily removable since it does not extend entirely around the garment.

While the garment is being sloped, the support of the cut fabric is desirable so that its weight does not affect the as yet uncut hem. On the underside of bed plate 104, which is integral with member 81, is pivoted, by means of the stud 105, the member 106 formed integral with the bearing block 107 in which the spindle 108 is journaled. A gear 109, keyed to the spindle 108, is driven by the gear 59, and a roller 110 is thereby caused to rotate and, bearing against the periphery of the feed member 58, insures the proper

support of the cut edge. A torsion spring 111, between the member 106 and the head of the stud 105, serves to urge the roller into firm contact with the feed member 58.

The cover division 63 is maintained in place by the bolt 112 removably securing said cover to the bracket 54 and access to that part of the device is afforded thereby. A handle 113 serves to enable the feeding and trimming unit to be manually swung about the post 31 into operative position relative to the form 23 and to be withdrawn when not in use.

After a garment has been placed on the form 23, the operator adjusts the arm 27 according to desire, the height being indicated by the indicia 26 on the rod 25. The pedal 28 is then depressed and the release of the usual gripping mechanism being thus accomplished, the form 23 may be manually raised or lowered to the height of the arm 27. The device at this stage is in the inoperative or outward position as seen in Fig. 1.

The pedal 28 having been released, the cutting and feeding mechanism is swung on the post 31 and the pedal 64 is depressed to allow of the insertion of the fabric between the unit 62 and the brush 103, between the feed members 58 and 42-43, and between the feed member 58 and the roller 110. The pedal 64 is then released. The width of the hem is ascertained and the arm 94 is adjusted accordingly.

The motors 16 and 35 are then started and the form 23 begins to rotate, the brush 93 maintains the fabric straight, the feed members 58 and 42-43, draw the fabric into the cutting zone, the circular blade 41, traveling at high speed, cuts the fabric, the roller 110 draws on the lower portion of the garment above and below the cut, and supports and draws the cut section away from the device while the wax marker 99, in combination with the ribs 103 of the drum 80, marks the intermittent hem-line.

The motors 15 and 35 are designed to operate at the same speeds and the reduction gearing 17 and 44 are of the same ratio so that the form 23, the drum 80, the feed members 58 and 42-43, and the roller 110 rotate at comparatively low speed, while the circular blade 41 rotates at a very high speed relative to these elements.

The instant devices makes possible the high-speed sloping of garments at a low cost and irrespective of the size of the garment being sloped.

Various elements contribute to effective and accurate sloping, but the expense of manufacture of the machine is very low relative to its accomplishments, the high-speed circular knife being particularly effective and simple as compared to shearing elements, different sizes of which are required for different sized dresses.

While the device has been illustrated as constituting a single manufacture, it can be made to operate on forms which are standard in the industry. Only adaptation to operatively connect the motor 16 to such a standard form would be required while the cutting mechanism would remain unchanged.

I claim:

1. A garment trimming machine comprising in combination a support for a garment, a rotating cutting member operating means therefor, feed means associated with and movable relative to said cutting member, and means for actuating said feed means to feed the material of said garment in the same direction as the movement of said cutter, although at a lower rate of speed.

2. A garment trimming machine comprising in

combination a support for a garment, means to rotate said support around its axis, a rotating cutting member and rotatable feed means associated with said cutting member, means for rotating said cutting member at a relatively high rate of speed, and means for rotating said support and feed means at a lower rate of speed than said cutting member.

3. A garment trimming machine for trimming the bottom of a garment supported on a form comprising a rotating cutting disk and feed means for engaging the bottom of said garment and feeding the fabric thereof to said cutting disk, said feed means including two peripherally opposed drum-like members rotating at a lower rate of speed than said cutting member, and between which said fabric is fed to be acted upon by said cutting member, one of said drum-like members having a peripheral groove formed therein to accommodate the edge of said rotating cutting member.

4. A garment trimming machine for trimming the bottom of a garment supported on a form comprising a rotating cutting disk and feed means associated with said cutting disk, said feed means comprising two cylindrical members adapted to engage and feed between them the fabric of said garment, one of said cylindrical members being split into two sections, said cutting disk being rotatably disposed between the split sections of said cylindrical member in a plane perpendicular to the longitudinal axis of said cylindrical member and having its cutting edge outwardly spaced from the periphery of said cylindrical member, said other cylindrical member being formed with a peripheral groove for accommodating said cutting edge of said cutting disk.

5. A garment trimming machine according to claim 4 wherein said cylindrical members rotate to feed the material of said garment toward said cutting disk, and said cutting disk rotates in the same direction although at a substantially higher rate of speed than said cylindrical members.

6. A garment trimming machine for cutting the bottom of a garment supported on a form, comprising a rotating cutting disk, rotating feed means associated with said cutting disk for engaging and feeding the fabric of said garment thereto, a drum-like member rotating with said feed means and having spaced ribs formed thereon parallel to the longitudinal axis of said drum-like member, a marking device adjacent to said drum-like member and adapted to bear against said ribs, said feed means being adapted to feed the fabric of said garment between said drum-like member and said marking device, whereby a mark is made on said fabric as said marking device contacts successive ribs during the rotation of said drum-like member.

7. A garment trimming machine for cutting the bottom of a garment supported on a form, comprising a rotating cutting disk, feed means for engaging and feeding the fabric of said garment to said disk and means disposed anterior to said feed means and cutting disk for drawing on said garment so as to straighten the fabric of wrinkles before it is acted upon by said feed means.

8. A garment trimming machine according to claim 7 wherein said drawing means comprises a brush rotating diagonally and bearing against the fabric of said garment.

9. A garment trimming machine comprising in combination, a support for a garment, a rotating cutting member, operating means therefor, feed means associated with and movable relative to

said cutting member including peripherally opposed, oppositely rotating members, additional means for rotating each of said feed members, and manually operable means to impart a bodily planetary movement to one of said members to an inoperative position relative to the opposed member and simultaneously disconnect the first named feed member from said last-named means.

10. A garment trimming machine comprising in combination, a support for a garment, a rotating cutting member, operating means therefor, feed means associated with and movable relative to said cutting member including peripherally opposed, oppositely rotating members, means for positively operating each of said feed members, means for mounting one of said members for yielding radial movement relative to the other during operation thereof, and manually operable means to impart a bodily planetary movement to the latter member to dispose said member in an inoperative position and disconnect the same from said operating means independently of the connection of the other feed member with said operating means.

11. In a garment trimming machine, a rotatable garment supporting form, a cutting station comprising a cutting knife, peripherally opposed, oppositely rotating feeding members having co-acting parts immediately adjacent to the cutting edge of the knife on opposite sides thereof, between which the garment material is received and fed to said cutting edge at both sides of the line of cut, and means for actuating said feeding members.

12. In a garment trimming machine, a rotatable garment supporting form, a feeding and cutting station comprising a cutting knife, peripherally opposed, oppositely rotating feeding members between which the garment fabric depending from the form is received and fed to said knife, means for rotating said members, and means co-operating with one of said members beyond the point of cut to support the material trimmed from the garment.

13. In a garment trimming machine, a rotatable garment supporting form, a feeding and cutting station comprising a cutting knife, peripherally opposed, oppositely rotating feeding members between which the garment fabric depending from the form is received and fed to said knife, means for rotating said members, a rotatable member peripherally co-operating with one of said feed members beyond the point of cut to support the material trimmed from the garment, and means operatively connecting said rotatable member with the means for rotating said feed members.

14. In a garment trimming machine, a rotatable garment supporting form, a rotatable cutting disk and operating means therefor, means for feeding the garment material depending from the form to said cutting disk, and a rotatable member mounted in advance of the point of cut to engage and apply tensioning stress to the garment material prior to its engagement by said cutting disk.

15. In a garment trimming machine, a rotatable garment supporting form, a rotatable cut-

ting disk and operating means therefor, means for feeding the garment material depending from the form to said cutting disk, and a diagonally positioned member in advance of the point of cut to engage and apply a lateral tensioning stress to the garment material prior to its engagement by said cutting disk.

16. In combination with garment trimming and feeding apparatus including cutting means and means for feeding the bottom portion of a garment to said cutting means, means for marking the garment material a predetermined distance above the line of cut simultaneously with the trimming operation, said means comprising a marking element, and relatively movable means operatively connected with said feeding means and co-operating with said element to produce a circumferentially spaced succession of marks on the garment material.

17. In combination with garment trimming and feeding apparatus including cutting means, a rotatable member for feeding the bottom portion of the garment material to said cutting means and operating means therefor; a drum fixed to said feed member over which the garment depends for engagement by said member, a marking element adjacent to the outer surface of said drum, and circumferentially spaced projections on the periphery of the drum co-acting with said marking element in the rotation of said drum to produce a circumferentially spaced succession of marks on the garment material simultaneously with the trimming operation.

18. In fabric feeding and trimming apparatus, a rotatable cutting disk, fabric feeding means associated therewith comprising peripherally opposed, oppositely rotatable cylindrical members between and by which the fabric is engaged and fed to the cutting edge of said disk, one of said feeding members having a circumferential groove in its periphery receiving the cutting edge of said disk.

19. In fabric feeding and trimming apparatus, a rotatable cutting disk, a cylindrical feeding member in adjacent co-axial relation with said disk, and means for rotating said disk and feed member in the same direction, at relatively different speeds, from a common source of power.

20. In fabric feeding and trimming apparatus, a rotatable cutting disk, feed means including cylindrical feed members at opposite sides of said disk in adjacent co-axial relation therewith, means for rotating said members in the same direction to feed the fabric to the cutting edge of said disk, and means for rotating the cutting disk in the same direction as said feed members but at a relatively higher speed.

21. In fabric feeding and trimming apparatus, a rotatable cutting disk, feed means including cylindrical feed members at opposite sides of said disk in adjacent co-axial relation therewith, means for rotating said members in the same direction to feed the fabric to the cutting edge of said disk, means for rotating the cutting disk in the same direction as said feed members but at a relatively higher speed, and a common operating motor for both of said two last named means.

JACOB SCHLESINGER.
